UNITED STATES PATENT OFFICE

LUIGO NEGRO, OF BUCHAREST, RUMANIA

NOZZLE

Application filed January 31, 1929, Serial No. 336,610, and in Italy February 15, 1928.

My present invention relates to a nozzle in which the same relations resulting from calculation may be kept up in any form or structure (such as devices for pushing and 5 hoisting, turbines, etc.), and the control of the liquid, gas or steam is effected on a large scale without changing the measure or degree of conicity.

My present improved nozzle comprises two 10 cones, the one engaged in the other, one of which is adapted to slide, and adjustable by means of a rod so that not only the relation between the outlet F_2 and inlet F_m is constant, but practically also the measure of conicity 15 equal to

$$\frac{\sqrt{F_2} - \sqrt{F_m}}{l}$$

where l is the distance between the two openings F_2 and F_m .

I have illustrated my invention by way of example in two of its modifications in the annexed drawings where

Fig. 1 is a symmetrical section of an ordinary nozzle for aeriform fluids,

Fig. 2 is also a symmetrical section, but of an improved nozzle according to my present invention, and

Fig. 3 shows a second modification thereof.

With reference to Fig. 1 and particularly its reference letters it is to be observed that when using nozzles u the smallest passage section F_m of which gradually broadens, there are two rather serious drawbacks, 35 namely:

1. It is known that to a certain given relation between the pressure P of the driving fluid (steam, compressed air, gas, etc.) ahead of the outlet, and the pressure P_o of chamber 40 C placed past the nozzle corresponds a certain degree of conicity determined by the surfaces F_2 and F_m and by the length l , and since the angle α of the diverging part ought to be as much as possible in accord with the

material inclination of the steam, it is just possible that in certain cases, such as e. g. the case of the example illustrated in Fig. 1, the length l of the diverging part of the nozzle,—as in correspondence with a determined 45 value of L , part l should not be of unallow-

able dimensions,—becomes so large that the device owing to its highly unsatisfactory efficiency is practically useless.

2. Generally the quantity of liquid, steam or gas is controlled by the needle t . From the above it will be seen that after having established the values F_2 — F_m and l when the area of section F_m of the outlet is reduced by the introduction of the control needle, the predetermined relation between the three values F_2 — F_m and l is varied and the efficiency is reduced to practically unallowable values.

My present invention relates to a nozzle type in which the relations resulting from calculation may actually be utilized and the controlling of the liquid may be effected on a large scale without exceeding the limits resulting from calculation for the degree of conicity.

The device according to my present invention, Fig. 2, comprises a cylindrical body 1, within which a cone 2 is fixed to a point 7 in any suitable mechanical way. In the cylinder 1 slides a ring 3 controllable by a rod 4. The outer surface of ring 3 is cylindrical, whilst the inner surface is conical so that the ring forms an annular space with cone 2, and in correspondence with a determined value of l the smallest section area F_m passes to the value F_2 which has been fixed by calculation of the nozzle. The said annular space is more or less large according to the ring 3 being shifted upwards or downwards by the needle 4 rotating in the boss 6 connected to ring 3 by wings 7.

It is obvious that the above described arrangement permits of making nozzles the length l of which most corresponds to a high efficiency of the device. The further advantage is obtained that the degree of conicity is practically constant for any admission of driving fluid, which is not obtainable by ordinary nozzles controlled by a needle as shown in Fig. 1.

It is understood that the modification shown in Fig. 2 may be varied without varying the purpose aimed at, as is shown e. g. in Fig. 3 where ring 3 is fixed to ring 1, and its cone is movable and operated by rod 4.

Having now particularly described and as-

certained the nature of my said invention and in what manner the same is to be performed I declare that what I claim is:

A nozzle including an outer hollow cone and an inner cone, said nozzle widening in section in the direction of the flow therethrough between the cones, the inner cone being engaged in the hollow cone and both being reciprocally slideable for adjustment, the nozzle being so shaped and the reciprocal position of the cones so arranged that when reciprocally sliding on the one hand the ratio between the outlet and the inlet section is substantially invariable, and on the other hand the measure of conicity is practically constant.
